ALARM MECHANISM.

1,331,694.

Specification of Letters Patent. Patented Feb. 24, 1920.

Application filed March 15, 1919. Serial No. 282,812.

To all whom it may concern:

Be it known that we, JAMES M. BUTCHER and EDMUND B. FUNSTON, citizens of the United States, and residents of Chicago, in the county of Cook and State of Illinois, and of Racine, in the county of Racine and State of Wisconsin, respectively, have invented certain new and useful Improvements in Alarm Mechanism, of which the following is a description, reference being had to the accompanying drawings, which form a part of our specification.

Our invention relates to alarm mechanisms more especially intended for use in connection with cash or jewel boxes or other containers for valuable documents and the like; the invention having for its object the provision of mechanism which will be positive in operation and of such simple and sensitive nature that its manipulation may be readily accomplished while at the same time operation of the mechanism quickly induced through the slightest movement of the container or box or an element movably secured 25 to the container to which the mechanism is applied.

Another object of our invention is to provide a construction whose positioning or alarm-sounding condition can be controlled from the container exterior by a suitable key, which can only be withdrawn from the key-receiving slot or socket after the alarm mechanism has been placed in "set" or alarm-effecting position.

Our invention also contemplates the provision of mechanism whereby an auxiliary or supplemental alarm may be sounded; the latter mechanism being preferably independently controlled so far as its "setting" or operative position is concerned; but operable by the same mechanism when said auxiliary alarm has been "set."

We have illustrated what we believe to be the simplest and best adaptation of our invention, as well as a modification thereof, but it will be understood that the invention may have expression in different mechanical form without, however, departing from the spirit of the invention as set forth in the appended claims; and the objects and advantages of the invention will be more fully comprehended from the following detailed description of the accompanying drawings, wherein:

Figure 1 is a perspective view of a type

of container or box to which our improved mechanism may be applied; the mechanism being adapted to be installed in one end of the container as shown in subsequent figures.

Fig. 2 is a perspective view of the interior of one end of the container or box provided with our improved mechanism which is illustrated in inoperative or non-set position.

Fig. 3 is a side elevation of the mechanism and interior of the box or container illustrating the mechanism in "set" position.

Fig. 4 is a view taken at right angles to Fig. 3, with only a portion of the end of the box or container illustrated; while the mechanism is shown in released or alarm-sounding position.

Fig. 5 is a detail sectional view of an auxiliary or supplemental alarm mechanism.

Fig. 6 is a detail view in perspective of a modified form of alarm tripping or releasing means.

In the particular exemplification of our invention, it is shown applied to a metal box of the type usually employed as a cash or jewel box; the mechanism being intended to be secured within the box and to one end wall thereof; with the mechanism preferably inclosed in a suitable housing so as not to be interfered with or affected by the contents of the box.

The mechanism, as illustrated in the first figures of the drawings, is intended to be tripped or released through movement of the container or box in which the mechanism is installed; that is, through any shifting of the container along the shelf or other element on which the container rests, or by lifting the container off the shelf or stand; while in the modification of the mechanism, the tripping or releasing is caused by the movement of a protruding portion adapted to have movement relative to the box or container.

The principal alarm mechanism may comprise any suitable bell or gong shown at 10, provided with the usual spring-driven mechanism controlled by a suitable 105 detent; the spring being usually controlled or wound through proper rotation of the bell or gong 10; the spring-driven mechanism, which is usually housed within the bell or gong is of a well known construction 110

and therefore needs no description nor detailed illustration.

The pinion 11 of the spring-actuated escapement is maintained against rotation by the pallet or detent 12 to which the striker 13 is secured; the vibratory movement of the striker element 13 being induced by lugs 14 on the detent 12 coming into striking or frictional engagement with the teeth of the escapement pinion 11. The detent 12 is held in holding position with pinion 11 by means of a collar or shoulder 15 on a spring-controlled pin 16 which extends through to the rear of the housing or shell of the alarm mechanism, as more clearly shown in Fig. 4. The position of the pin 16, namely with its collar or shoulder 15 in holding engagement with detent 12 is controlled by means of a coil spring 17. The pin 16 is adapted to have movement in a lengthwise direction so as to enable the collar or shoulder 15 thereof to be moved out of contact with detent 12; and such movement of pin 16 is controlled by means of a finger 18 secured on the inner end of a rock-shaft 19. The finger 18 and rock-shaft 19 are under spring tension by means of a spring 20 shown disposed about the rock-shaft and adapted to rock the shaft 19 in a direction which will force finger 18 toward the end of pin 16. The rock-shaft 19 is horizontally disposed and rockingly mounted in a suitable bracket or housing. Secured to rock-shaft 19 is a bell-crank lever 21, one end thereof is shown disposed through a slot in the supporting bracket or frame 22, while the other end is disposed forwardly in a horizontal direction and engages with a reciprocating member or vertically movable plunger 23 which is slidably mounted in the bracket or housing 22. The lower end of the member or plunger 23 is shown provided with an off-set foot or extension 24 which provides a support for a loosely suspended pendulum member 25 so as to retain the upper end of the stem portion of the pendulum member in proximity to the lower end or surface 23^a of the main portion of the plunger 23; the foot portion 24 being of such construction as to permit pendulum member 25 to swing freely to either side of its vertical axis; while at the same time causing the pendulum 25 to move upwardly or downwardly with the plunger 23 when the latter is reciprocated through the manipulation of a key-controlled tumbler or stem mounted in the barrel 26. The barrel 26 is suitably mounted on the bracket or frame 22 and to the wall of the cash box or container so as to have the end of the barrel 26 extend through or into a suitable opening in the end wall of the container or box, as shown at 27 in Figs. 1 and 4. The inner end of the tumbler or stem, within barrel 26, is provided with a cam or eccentrically mounted disk 28 which is adapt-

ed to engage with a pin 29 secured to the upper end of reciprocatingly mounted member or plunger 23. The cam 28 is so secured to the tumbler or key-controlled stem that the eccentric portion thereof will force plunger 23 upwardly and move the alarm mechanism into inoperative position. The portion of the cam or disk 28, adjacent the stem or tumbler, is slotted adjacent its periphery as shown at 30 in Figs. 2 and 3; the slot 30 being open ended so as to receive the pin 29 when the disk or cam is rotated through a proper turning of the key-controlled stem or tumbler whereby the eccentric portion of the disk is moved into a position below its axis 75 as shown in Fig. 3. Such rotation of the disk will cause the pin 29 to enter the slot 30 and thus hold plunger 23 in its downward position and prevent any improper movement of plunger member 23; that is to say plunger member 23 will be held in its downward and "set" position until cam or eccentric member 28 has been rotated by means of the key-controlled tumbler or stem.

Pivottally mounted in the frame or bracket-portion 22 and disposed vertically beneath the mounting of bell-crank lever 21 is a rod 31, to the lower end whereof is secured a cover plate or member 32 which is adapted to close an opening 33 formed in the bottom of the box or container at a point in vertical alinement with pendulum member 25. The opening 33 in the box is intended to permit the pendulum to come into frictional contact with the shelf or table on which the container rests and also permit downward movement of the pendulum when the box is lifted from the shelf. The rod 31 is preferably shown provided with a lug or finger 34, see Fig. 2, which is adapted to be engaged by the lower or depending end of bell-crank lever 21, as shown at 35 in Fig. 2; and the rod or stem 31 is also shown provided with a spring 36 coiled thereabout; with one end of the spring suitably secured to the bracket 22, as shown in Fig. 4, while the opposite end is shown disposed about or in operative contact with the lug or finger 34, which latter is firmly secured to rod or stem 31 so as to oscillate therewith. The spring 36 is so secured that it will induce rod 31 to rotate, when the lower end 35 of bell-crank lever 21 is moved out of contact with lug or finger 34 so as to cause plate 32 to swing away from opening 33 in the bottom of the box or container and thereby uncover the opening so as to permit pendulum member 25 to depend into the opening 33 in the manner shown in Fig. 3, namely with the lower end of the pendulum 115 in frictional contact with the shelf or element on which the box or container is placed.

Assuming that the alarm proper 10 has its energizing spring suitably wound (the winding being usually effected by rotating 130

the bell or gong proper), the alarm mechanism is then "set", after having first placed the box on the shelf where it is to remain, by means of a suitable key inserted in the opening 27 of the box or container and barrel 26 so as to rotate the tumbler or stem within barrel 26 in such direction that the eccentric portion of disk or cam 28 will be disposed below the key operated stem or tumbler, namely into the position shown in Fig. 3, and pin 29, at the upper end of plunger 23, will have entered the open ended slot 30 of the cam, thereby locking plunger 23 against any upward movement. Plunger 23 member 23 is caused to move downwardly when cam 28 is rotated in the manner just described, through the action of the spring 20 on the rock-shaft 19 to which bell-crank lever 21 is secured; the force of spring 20 being transmitted to plunger 23 by the outer end of bell-crank lever 21 which is disposed in a slot 37 of plunger 23, see Figs. 2 and 3.

Plunger 23 will therefore be positively moved downwardly and at the same time carry pendulum 25 with it so that the latter will be disposed slightly through opening 33 in the bottom of the box or container and therefore in frictional contact with the shelf or other element on which the box or container rests. The pendulum 25 has free swinging relation with the portion 24 of plunger 23; this relation in the particular exemplification shown in the drawings being somewhat in the nature of a ball and socket connection at 38; while the upper end of the stem portion of the pendulum is preferably slightly rounded and forced into frictional contact with the smooth surfaced end 23^a of plunger 23 by reason of the pendulum coming into contact with the shelf and thereby arresting further downward movement of plunger 23 induced by spring 20 and lever 21. The relation between the upper end of the pendulum and the surface 23^a is such that the slightest force encountered by the lower end of the pendulum through shifting of the box on the shelf, or release of the pendulum caused by the lifting of the box from the shelf, will cause the upper end of the stem of the pendulum 25 to either slip on the surface 23^a and therefore induce the pendulum 25 to swing to one side of its vertical axis, or move downwardly through the hole 33 and release plunger 23 so that it may move to its maximum depressed position through the action of spring 20 on rock-shaft 19. During the downward movement of plunger 23, after the box has been placed on the shelf, the foot portion 23^a will come into contact with the stem of pendulum 25 and, by reason of the contact of pendulum 25 with the shelf, table or other element on which the box or container rests, the pendulum will

prevent plunger 23 from moving to its extreme lowest position, so that the plunger 23 and the rock-shaft 19, to which bell-crank lever 21 is rigidly secured, will be held under spring pressure induced by spring 20. Arresting of plunger 23 in its downward movement as described will also arrest movement of bell-crank lever 21, rock-shaft 19 and finger 18; while spring 20 is exerting pressure on finger 18 in a direction toward pin 16. As long as pin 16 is in normal position, due to the action of its spring 17, the collar or shoulder 15 will remain in holding contact with detent 14 and cause the latter to hold pinion 11 against rotation. As is evident from the construction shown and described, the slightest movement of pendulum 25 toward one side of its vertical axis, or in further vertical direction as the case may be, will allow further downward movement of plunger 23, due to the action of spring 20 and thus cause finger 18 to force pin 16 inwardly against the action of its spring 17 and thereby move collar 15 out of holding engagement with detent 14, with the result that detent 14 will be prevented from holding pinion 11 against rotation. The movement of collar or shoulder 15 out of holding engagement with detent 14 permits the latter to have free oscillation or vibratory movement of the detent 14 causing the striker 13, secured thereto, to ring the bell or gong.

In addition to the alarm mechanism just described, we also disclose an auxiliary alarm, preferably in the nature of hammer or trigger mechanism adapted to explode or fire a shell which is shown at 39 placed in a suitable holder or barrel member 40. The holder 40 is shown having slot and pin connection, at 41 with the housing or side of the box so as to permit the holder 40 to be moved upwardly out of horizontal alignment with the end of the trigger containing housing 42 which is shown disposed horizontally above the alarm or gong 10 and rearward of the housing of the gong or bell 10. The housing 42 has a trigger or plunger 43 slidably mounted therein; the trigger or plunger 43 being provided with an upwardly disposed lug or finger 44 which passes through a slot 45 formed in the top of the housing 42, see Figs. 2 and 5. The plunger or trigger 43 is provided with a coil spring 46 shown disposed about the trigger rearward of the lug or finger 44, while the other end of the spring presses against the end wall or lug of the housing 42. It is evident that rearward movement of plunger or trigger 43 will compress the spring 46 and thereby place the plunger or trigger 43 under spring pressure which tends to force plunger 43 toward the cartridge or shell 39. The plunger or

trigger 43 passes through an opening in the end wall of the housing 42 and is provided with a notch 47 on the lower surface thereof which is adapted to engage with the end wall of the housing 42 when the plunger or trigger 43 has been drawn back against the action of spring 46, with the rear end of the trigger disposed through the closed end of the housing, as shown in Fig. 5. The action of spring 46 will also slightly depress the plunger or trigger 43 and cause notch or shoulder 47 to engage with the end wall of the housing 42 and thus hold the trigger 43 in its retracted or "set" position, namely 15 with the forward or pointed end thereof at a distance removed from the cartridge holder 40; it being understood, of course, that the forward end of the housing 43 is open or provided with an opening in alignment with 20 the tip or point of the plunger and also with the center of the cartridge, namely in alignment with the percussion cap in the cartridge. Pivottally mounted on a post 48 on the housing of the alarm mechanism, or on 25 the end wall of the box or container, is a tripper member 49; with one end thereof in sliding engagement with the bottom of the trigger 43, while the other end is disposed in the path of a finger 50 secured to the 30 main spring winding key or post 51 of the gong 10; the finger 50 being so secured to the key or post 51 as to rotate therewith when the bell is rung through the proper operation of detent 14; the ringing of the bell or 35 unwinding of the main spring causing the key-post 51 to revolve as is usual in alarm bells of the class shown in the drawings. Rotation of finger 50 will force it into engagement with tripper 49 and cause the latter to 40 move in clockwise direction in Fig. 5, which will cause the upper end of the tripper 49 to force the rear end of trigger 43 upwardly sufficient to move the notch 47, or rather the shoulder thereof, out of engagement with 45 the wall of the housing 42 and permit spring 46 to exert its tension on trigger 43, causing the latter to fly forwardly into striking engagement with the cartridge 39, so as to cause the latter to explode and produce a report 50 or auxiliary alarm at the same time bell or gong 10 is being sounded. When it is merely desired to use the bell or gong, the trigger 43 will be left in the non-firing position, shown in Fig. 2.

55 In Fig. 6 we show a slight modified form of our invention, wherein the box or container is provided with a loosely mounted slide or projection 52, having one end disposed through an opening in the side wall of the container, while the inner end is arranged beneath the pendulum 25 to support the same in frictional relation with the bottom of plunger 23 when the mechanism has been set. As is evident from the construc-

tion shown, a slight movement of slide or 65 projection 52 will cause pendulum 25 to move out of proper vertical alignment with the plunger 23 and therefore out of holding contact with the bottom of plunger 23, which will allow spring 20 to force finger 18 against 70 the end of pin 16 and release the detent 14.

The slide 52 is shown provided with an aperture 53, whereby a suitable dark thread, string, or fine wire may be secured to the slide and be strung or led across the path 75 leading to the box or container, in such a manner that an unauthorized person will come into contact with the thread (the other end whereof is suitably secured to some stationary object) and thereby exert a pull on 80 the slide 52 so as to move the inner end thereof and cause the pendulum 25 to swing side-wise out of holding relation with plunger 23.

It is apparent that our improved construction may readily be employed as a burglar 85 alarm, by simply inclosing the mechanism in a suitable container made just large enough to hold the mechanism so as to adapt it being set or placed in a dresser-drawer or other desired place; and the mechanism be tripped 90 or set off either through the use of a string, or through movement of the container.

What we claim and wish to secure by Letters Patent is:—

1. Alarm mechanism of the class described, adapted to be installed in a container, comprising an energized alarm element provided with an escapement, spring-controlled means normally adapted to control the escapement and prevent sounding of the alarm element, reciprocatingly mounted means, operable from the container exterior, normally tending to move in one direction, said means being adapted to force said first mentioned means against the action of its spring and thereby release said escapement, and gravity-actuated means adapted, when disposed in longitudinal alignment with the reciprocating means, to arrest final movement of the reciprocatingly mounted means whereby the spring-controlled means are left in normal escape- 105 ment holding position.

2. Alarm mechanism of the class described, comprising a spring-controlled 115 alarm element provided with an escapement whereby action of the spring is arrested, spring-controlled slidable means normally adapted to arrest said escapement, vertically movable means adapted to control said 120 spring-controlled means, means whereby said vertically movable means are yieldingly forced downward and the first means controlled, a key-controlled cam adapted to raise said vertically movable means, and a 125 pendulum freely mounted beneath said vertically movable means and adapted, when in direct alignment with said means, to ar-

rest the downward movement of the vertically movable means against the yielding force of said third means.

3. Alarm mechanism of the class described, adapted to be installed in a container, comprising an energized alarm element, spring-controlled means whereby said alarm element is controlled, vertically movable means arranged to control said spring-controlled means, a key-controlled cam operable from the carrier exterior and adapted to position said vertically movable means, and a pendulum mounted beneath said vertically movable means and adapted to be disposed through an aperture in the bottom of the container, said pendulum, when in vertical alinement with the vertically movable means and when said aperture is covered, being adapted to arrest further downward movement of the second mentioned means, while downward or sidewise movement of the pendulum will release the second mentioned means and permit the spring-controlled means to release said alarm element.

4. An alarm mechanism adapted to be installed in a container, comprising an alarm element, a spring-controlled member adapted to control the alarm element, a vertically movable plunger having operative relation with the spring-controlled member so as to hold the latter against the action of its spring, a pendulum member adapted to have vertical and oscillatory movements and adapted to be disposed in direct alinement with and beneath said vertically movable plunger, said pendulum member being arranged to hold said plunger member against continued downward movement through the action of said spring-controlled member when the pendulum member is in vertical position, and key-controlled means operable from the container exterior and arranged in operative relation with said vertically movable plunger whereby vertical movement of the plunger is controlled and positioning of the spring-controlled member is determined.

5. Alarm mechanism adapted to be installed in a container, comprising an energized alarm element, a spring-controlled rock-shaft adapted to control the release of said alarm element, a vertically movable plunger operatively connected with said rock-shaft so as to control the movement of the latter, key-controlled means having operative relation with said vertically movable plunger, and a vertical and sidewise moving pendulum adapted to swing into vertical alinement with said plunger so as to arrest its continued downward movement when the pendulum is held against vertical movement, said pendulum being adapted to be affected from the container exterior and be moved out of vertical alinement with

said plunger and thereby release the spring-controlled rock-shaft and sound the alarm. 65

6. Alarm mechanism of the class described, adapted to be installed in a container, comprising an energized alarm element, a spring-controlled rock-shaft whereby the sounding of the alarm is controlled, a vertically movable plunger operatively connected with said rock-shaft so as to hold the latter against the action of its spring, key-controlled means arranged in operative relation with said plunger and controllable from the container exterior, and a vertically and sidewise moving pendulum mounted beneath said plunger and controllable from the container exterior, said pendulum being 80 adapted to arrest the plunger against further downward movement when said pendulum is in vertical alinement therewith and held against movement.

7. An alarm mechanism of the class described, adapted to be installed in a container, comprising a spring-controlled alarm provided with an escapement, a rock-shaft adapted to control the pallet of the escapement of said alarm, a vertically slidable plunger connected with said rock-shaft, the plunger and rock-shaft being spring-actuated so as to induce downward movement of the plunger and movement of the rock-shaft, whereby the pallet of the escapement 95 is released when the rock-shaft and plunger reach the maximum point of their movements, loosely swinging means disposed in the path of said plunger and adapted to hold the latter, with the rock-shaft, against complete movement through the action of the spring, said means being adapted to be affected from the container exterior, and key-operated means whereby said plunger and rock-shaft may be positioned. 100

8. An alarm mechanism of the class described, adapted to be installed in a container, comprising an energized alarm element, a spring-controlled rock-shaft adapted to control operation of said alarm element, a vertically movable plunger operatively connected with said rock-shaft so as to cause the rock-shaft and plunger to move in unison, tripping means adapted to be disposed, when the mechanism is in "set" position, in 115 an opening in the container and arranged beneath said plunger, said tripping means being adapted to prevent the plunger from moving into its maximum depressed position, said tripping means being adapted to move into releasing position through movement of the container whereby the tripping means is caused to move either vertically or in sidewise direction.

9. In alarm mechanism of the class described, the combination of an energized alarm element, with a spring-controlled slideable plunger, means whereby said plunger

may be arrested against the action of its spring, a cartridge-holding member slidably and removably secured in alignment with the plunger, a pivotally mounted tripper arranged in contact with said plunger and adapted to release the latter from said first means, and means operable with the alarm element and adapted to oscillate the pivotally mounted tripper so as to induce the latter to force the plunger out of arrested relation with the first means.

10. Alarm mechanism of the class described, adapted to be installed in a container, comprising an energized alarm element, spring-actuated means whereby said alarm element is controlled, a vertically movable member arranged in operative relation with said spring-actuated means whereby the latter is held against the energy of its spring, a key-controlled cam operatively connected with the upper end of said vertically movable member whereby the positioning of the latter is controlled, said cam being adapted to lock said vertically movable member against improper upward movement, and vertically and sidewise moving means mounted beneath said vertically movable member and adapted to prevent downward movement of said member when 25 said last mentioned means is in vertical alignment with said vertically movable member, said means being adapted to be affected from the container exterior and thereby caused to move in either vertical or sidewise direction.

11. Alarm mechanism of the class described, adapted to be installed in a container and comprising an energized alarm element, a spring-controlled rock-shaft 40 adapted to control said alarm element, a vertically movable plunger operatively connected with the rock-shaft so as to prevent movement of the latter through the action of its spring, key-controlled means operable

from the container exterior whereby the 45 vertically movable plunger and said rock-shaft may be controlled, a vertically and sidewise moving pendulum adapted to swing into vertical alignment with said plunger and arrest the movement thereof, said pendulum being adapted to be affected from the container exterior so as to be moved out of vertical alignment with the plunger and thereby release the latter and said rock-shaft and cause the alarm element to operate. 50 55

12. Alarm mechanism of the class described, adapted to be installed in a container and comprising a spring-controlled alarm element provided with an escapement, a rock-shaft adapted to control the pallet 60 of the escapement of said alarm, a vertically slidable plunger connected with the rock-shaft, the plunger and rock-shaft being spring-actuated so as to induce downward movement of the plunger and rocking 65 movement of said shaft, whereby the pallet of the escapement is released when the rock-shaft and plunger reach the maximum point of their movements, a vertically and side- 70 wise movable pendulum disposed in the path of said plunger and adapted to hold the latter, with the rock-shaft, against complete movement through the action of the spring, and tripping means adapted to support said pendulum in the path of said 75 plunger, said tripping means being adapted to be affected at a point removed from said mechanism and thereby cause the pendulum to move out of the path of said plunger and permit the latter with said rock-shaft to 80 complete the movement induced by said spring.
